UNITED STATES PATENT OFFICE.

GOODRICH Q. LEWIS, OF WHEATON, ILLINOIS, ASSIGNOR TO WILLIAM H. MINER, OF CHAZY, NEW YORK.

FRICITION DRAFT-GEAR.

1,278,360.

Specification of Letters Patent. Patented Sept. 10, 1918.

Application filed July 13, 1916. Serial No. 109,001.

To all whom it may concern:

Be it known that I, GOODRICH Q. LEWIS, a citizen of the United States, residing at Wheaton, in the county of DuPage and State of Illinois, have invented a certain new and useful Improvement in Friction Draft-Gears, of which the following is a full, clear, concise, and exact description, reference being had to the accompanying drawings, forming a part of this specification.

This invention relates to improvements in friction draft gears.

The object of the invention is to provide a friction draft gear for railway cars, of simple arrangement, composed of few parts, and wherein the friction gear may be readily inserted and removed.

The invention furthermore consists in the improvements in the parts and devices and in the novel combinations of the parts and devices herein shown, described and claimed.

In the drawing forming a part of this specification, Figure 1 is a longitudinal, vertical section of a draft rigging embodying my invention. Fig. 2 is a horizontal, longitudinal section taken on the line 2—2 of Fig. 1. Fig. 3 is a transverse, vertical section taken substantially on the line 3—3 of Fig. 1. And Fig. 4 is a perspective view of the improved friction cylinder employed in my arrangement.

In the drawing forming a part of this specification, 10—10 denote channel center sills between which is mounted and secured thereto a rear abutment block or stop 11. The draw bar 12 is operatively connected to the friction gear, hereinafter described, by a horizontal yoke 13 and coupler key 14, the yoke 13 abutting at its rear end, said stop 11 and adapted to remain stationary in buff. Mounted within the yoke is the friction mechanism designated generally by the reference A. The friction mechanism A, as shown, comprises a casting having a rectangular spring cage portion 15 and friction cylinder 16. Where the cage and cylinder coalesce at the top, the casting is provided with a transverse, upstanding flange 17 forming a shoulder which is arranged to engage a horizontal, transversely extending upper stop casting 18, the latter being riveted or otherwise suitably secured to the top flanges of the center sills, as indicated in Fig. 3. Said flange 17 is suitably rein-

forced by tapering flanges 19—19. The stop casting 18 is provided at its rear with a vertical flange 20 which is also suitably reinforced by tapering flanges 21. At its rear, and near the bottom thereof, the friction shell and spring cage casting is provided with laterally extended shoulders 22—22 suitably reinforced by tapered flanges 23. The shoulders 22 engage and cooperate with a pair of stop castings 24 secured to the lower portions of the center sills. Each of said stop castings 24 comprises a vertical, rear stop wall 25, vertical flange 26 secured against the vertical web of the center sill, and a horizontal flange 27 fitting against and secured to the underside of the lower flange of the center sill. Each stop 24 is further provided with an upper horizontal flange 28 which forms a guide and support for the yoke 13. The friction gear is held in operative position by means of two tie plates 29—29 detachably secured to the lower flanges of the sills.

In draft, it is apparent that the friction shell is prevented from forward movement due to the coöperating three sets of stops and shoulders. The wedge and friction shoes, however, are actuated by the horizontal yoke through the rear follower. In buff, the yoke and follower are held stationary against the abutment block 11, thus preventing rearward movement of the wedge. The friction shell A moves rearwardly in unison with the draw bar, thus actuating the friction mechanism, as will be understood.

From the preceding description, it will be seen that the strains are transferred, under draft, to the sills at widely distributed points, to an upper horizontal stop, and to two vertical side stops. Furthermore by the arrangement provided, it is possible to insert and remove the friction shell while the draw bar and yoke are in place, thus facilitating repairs when the car is on the road.

I claim:

1. In a draft rigging, the combination with sills, of an upper horizontal stop secured thereto, side stops secured to the inner faces of the sills, and a friction shell having shoulders coöperable with said stops.
2. In a draft rigging, the combination with sills, of an upper stop extending horizontally between and secured to said sills,

side stops secured to the inner faces of the sills, a horizontal yoke, and a friction shell insertible vertically between the arms of said yoke while the latter is in position, said shell having shoulders coöperable with all of said stops.

3. In a draft rigging, the combination with sills, of an upper horizontal stop secured thereto, side stops secured to the inner faces of the sills, and a friction shell having shoulders coöperable with said stops, said stops and shoulders being so arranged as to prevent forward movement of the friction shell.

4. In a draft rigging, the combination with sills, of a rear abutment block mounted between and secured to said sills, a plurality of stops secured to said sills, a friction shell having shoulders coöperable with said stops whereby the shell is prevented from forward movement, and a horizontal yoke, said shell being removable from below.

5. In a draft rigging, the combination with sills, of a rear abutment block mounted between and secured to said sills, a horizontal yoke, a plurality of stops secured to said sills, a friction shell having shoulders coöperable with said stops, said shell being insertible and removable from below while said yoke is in position.

6. In a draft rigging, the combination with sills, of a rear abutment block mounted between and secured to said sills, an upper, horizontally extending stop, side stops secured to the inner faces of said sills near the bottom thereof, a horizontal yoke, and a friction shell mounted between the arms of said yoke and having top and side shoulders coöperable with said stops.

7. As an article of manufacture, a friction shell for draft rigging, said shell having an upper shoulder and two side shoulders coöperable with correspondingly arranged stop members.

8. As an article of manufacture, a combined friction shell and spring casing, the spring casing being of substantially rectangular formation, said shell and casing having an upper, transversely extending shoulder and vertically extending shoulders on opposite sides thereof near the bottom, said shoulders being coöperable with correspondingly located stop members.

In witness that I claim the foregoing I have hereunto subscribed my name this 11th day of July, 1916.

GOODRICH Q. LEWIS.
